Attorney

UNITED STATES PATENT OFFICE.

JOHN A. FREEZE, OF SAYREVILLE, NEW JERSEY.

COLLAPSIBLE CHAIR.

Application filed September 21, 1922. Serial No. 589,575.

To all whom it may concern:

Be it known that I, JOHN A. FREEZE, a citizen of the United States of America, residing at Sayreville, in the county of Middlesex and State of New Jersey, have invented certain new and useful Improvements in Collapsible Chairs, of which the following is a specification.

This invention relates to certain new and useful improvements in collapsible chairs, and has for its primary object thereof the provision of a novel form of folding chair wherein the chair back and legs are folded in directions toward each other to occupy positions adjacent the seat whereby the chair assumes a folded compact form enabling the same to be stored in a relatively smaller space as would not be the case of a chair of a rigid construction.

With the above and other objects in view as the nature of the invention is better understood, the same consists in the novel form, combination and arrangement of parts hereinafter more fully described in connection with the accompanying drawings, and in which like reference characters designate corresponding parts throughout the several views.

In the drawing,

Figure 1 is a side elevational view of my device, the chair being shown in its rigid set up position,

Figure 2 is a side elevational view of the chair in its collapsed position,

Figure 3 is a fragmentary transverse vertical sectional view upon the broken lines III—III of Fig. 1,

Figure 4 is a longitudinal cross sectional view upon the lines IV—IV of the same figure.

Figure 5 is a view similar to Fig. 4, but taken upon the broken lines V—V of Fig. 1,

Figure 6 is a fragmentary cross sectional view upon the lines VI—VI of Fig. 3 showing more clearly the relation of one of the rear pivoted legs with its supporting structure,

Figure 7 is a fragmentary perspective view of the upper portion of one of the rear legs of the chair, and

Figure 8 is a rear elevational view of the rear connecting bar for the under structure of the chair.

The preferred embodiment of the pres-

ent invention resides in the provision of a rectangular seat portion 1 having side depending skirt portions 2 and 3 and a similar front depending skirt portion 4. A pair of front legs 5 are pivotally connected adjacent their upper ends as at 6 adjacent the forward ends of the depending skirt portions 2 and 3 of the rectangular seat 1, it being noted that the pivot 6 for these front legs is in the form of a cross rod 7 extending transversely beneath the seat 1 and headed at its outer ends. A seat back 8 is pivotally connected at 9 adjacent the rear end of the said depending skirt portions 2 and 3 of the seat 1, this seat back being provided with depending side extensions 10.

A subframe is associated with the front legs 5 and the depending back extensions 10, the same embodying a forward cross bar 11, side bars 12 and a rear cross bar 13, the side bars 12 being pivotally connected as at 14 adjacent their forward ends to the front legs 5 at points spaced from the upper ends of the front legs, while the rear ends of the side bars 12 of the subframe are pivotally connected as at 15 to the lower ends of the seat back extensions 10. Rear corner legs 16 are pivotally supported at the connection 15 inwardly of the side bars 12 of the subframe. These rear legs 16 are formed as shown in Fig. 7, each comprising a main leg portion 16' having a right angularly bent side strip 16'' formed thereon and extending the complete length of the main portion 16'. The upper edge of the side strip 16'' is curved as shown for allowing this portion of the legs to be swung about its pivot connection 15 for engaging beneath inwardly extending side flanges 12' formed on the side bars 12 of the subframe, it being noted that this side strip of the legs 16 is suitably perforated to engage over the pivotal connection. The rear cross bar 13 of the subframe is provided adjacent its end portion with vertically extending slots 13' for allowing the side strips 16'' of the rear corner legs to extend therethrough, the lower edge of this rear bar 13 being notched at its opposite ends at 13'' for permitting free swinging movement of the rear legs upon their pivot connections, it being further understood that the upper ends of the main portions 16' of the rear

legs have close contact with the adjacent wall of the rear connecting bar 13 when the chair is in its set up position as shown in Figs. 1, 3, 4 and 5.

5 In collapsing the chair to cause the same to be moved from the set up position shown in Figs. 1, 3, 4 and 5, to the collapsed condition shown in Fig. 2, link connections between the legs are provided, the same including the provision of elongated slots 17 in each of the side bars 12 of the chair subframe for the sliding reception of a pivot pin 18. A link 19 pivoted to each of the pins 18 at their inner ends is pivotally connected as to 20 to the rear corner legs 16 at a point spaced beneath the hinge connection 15 while a second link 21 pivoted to the pin 18 has the other end thereof pivoted to the hinge connections 6 between 10 the front legs 5 and the side depending skirt portions 2 and 3 of the chair bottom. 1. As a means for preventing the sliding movement of the pivot pins 18 within the slots 17 and for consequently allowing the 15 chair to be extended to a folded position as shown in Fig. 2, the pivot connections 15 between the back extensions 10 and the subframe have freely swingingly mounted thereon arm members 22 notched adjacent 20 their outer ends as at 23 for engaging over the said pivot pins 18 when the chair is in its set up position as shown in Fig. 1. These arms 22 may be provided with side extensions 24 upon the forward end thereof 25 for facilitating the easy actuation of these arm members. When the notched ends 23 of the arm members 22 engage over pivots 18 when the chair is in a set up position as shown in Fig. 1, these arm members will 30 effectively prevent the collapsing of the chair. These arm members are so arranged as to assume a position substantially as shown in Fig. 2 when the chair is collapsed.

The pivot connections 15 and 20 at opposite sides of the subframe structure are shown as being in the form of annular-shaped cross rods 15' and 20' respectively, the outer ends of these cross rods are reduced as shown in Fig. 3 for defining annular shoulders 15" and 20" adjacent their outer ends, the reduced outer ends of these rods functioning as the pivotal connections 15 and 20. In view of this structure it will be clearly understood that a tight relation 50 is established between the elements pivotally secured to the ends of each of these rods, the same being in close relation between the annular shoulders thereon and the outer headed ends.

60 From the above description it is believed that the operation and advantages of the present invention will be readily understood by those skilled in the art, and while there is herein shown and described the preferred 65 embodiment of the present invention, it is

nevertheless to be understood that minor changes may be made therein without departing from the spirit and scope thereof.

What is claimed is:

1. In a chair of the type described, a seat bottom, front legs hinged to the forward edge of the seat bottom, a chair back hinged to the rear edge of the seat bottom, downward extensions carried by the seat back, rear legs associated with the downward extensions, a subframe hinged to the front legs and associated with the back extensions, means connecting the forward legs to the rear legs to cause the same to move in directions toward the chair bottom when the chair is collapsed, and locking means associated with said back extensions for engaging a portion of the leg connecting means when the chair is in a set up position for preventing collapsing of the same. 85

2. In a chair of the type described, a seat bottom, front legs hinged to the forward edge of the seat bottom, a chair back hinged to the rear edge of the seat bottom, downward extensions carried by the seat back, rear legs hinged to the downward extensions, a subframe hinged to the front legs and to the back extension, connecting links pivotally connected to the front legs at a point above the subframe connection and to the rear legs to cause the legs to move in directions toward the chair bottom when the chair is collapsed, and pivoted hook members carried by the back extensions for engaging over the connections for said links when the chair is in a set up rigid position for preventing collapsing of the same. 90

3. In a chair of the type described, a seat bottom, front legs hinged to the forward edge of the seat bottom, a chair back hinged to the rear edge of the seat bottom, depending extensions carried by said back, a cross rod journaled to said extensions, rear legs journaled to said cross rod, a subframe hinged to the front legs and cross rod, guideways formed in the side of said frame, links associated with said front legs, links associated with said rear legs, pivot pins connecting the free ends of said links and slidably engaging said guideways, and locking arms swingingly mounted on said cross rod and adapted to engage said pivot pins for preventing collapsing of the chair. 100

4. In a chair of the type described, a seat bottom, front legs hinged to the forward edge of the seat bottom, a chair back hinged to the rear edge of the seat bottom, depending extensions carried by said back, a cross rod journaled to said extensions, rear legs journaled to said cross rod, a subframe hinged to the front legs and cross rod, guideways formed in the sides of said frame, links associated with said front legs, links associated with said rear legs, pivot pins connecting the free ends of said links and 115 120 125 130

slidably engaging said guideways, and arm members mounted on said subframe to freely swing thereon and provided with notches adjacent their outer ends for engaging over said pivot pins for preventing sliding of the pivot pins within the guideways when the chair is in a set up position.

5. In a chair of the type described, a seat bottom, front legs hinged to the seat bottom, 10 a chair back hinged to the seat bottom, depending extensions carried by the seat back, a cross rod journaled to the lower ends of said extensions, a subframe journaled on said cross rod and pivoted to the front legs 15 below their pivot points on the seat, the subframe having elongated guide slots formed in its side, rear legs journaled on said cross rod, links associated with the seat pivots for the front legs, links pivoted to 20 the rear legs below their pivot points, pivot pins connecting the free ends of said links and slidably engaging said elongated slots, and arms pivoted to said cross rod having notches formed adjacent their outer ends 25 that are adapted to engage said pivot pins

for preventing the collapsing of the chair when in a set up position.

6. In a chair of the type described, a seat bottom, front legs hinged to the seat bottom, 30 a chair back hinged to the seat bottom, depending extensions carried by the seat back, a cross rod journaled to the lower ends of said extensions, a sub-frame journaled on said cross rod and pivoted to the front legs 35 below their pivot points on the seat, the subframe having elongated guide slots formed in its sides, rear legs journaled on said cross rod, links associated with the seat pivots for the front leg, links pivoted to the rear legs below their pivot points, pivot 40 pins connecting the free ends of said links and slidably engaging the elongated slots, arms pivoted to said cross rod having notches formed adjacent their outer ends that are adapted to engage said pivot pins 45 for preventing the collapsing of the chair when in a set up position, and side extensions carried by said arms for actuating the same.

In testimony whereof I affix my signature.
JOHN A. FREEZE.
